J. H. Long.
Letters Patent

7372 X

The Schedule referred to in these Letters Patent and making part of the same containing a description in the words of the word J. H. Long himself of his improvement in the Locomotive Steam Engine & other Rail Road carriages.

The improvements here contemplated have for their object greater economy and efficiency in the construction and use of Rail Road carriages, generally and especially of carriages propelled by steam on Rail Roads, greater simplicity & compactness in the construction & arrangement of these carriages and a more direct & safe & uniform application of motive steam power than has heretofore been attained in the construction of machinery for similar purposes.

These improvements consist in the invention of new machinery and parts of machinery never before used in any way known to the applicant, of new modifications of machinery and parts of machinery before known but now for the first time introduced in the construction of Rail Road Carriages and Locomotive Steam Engines, and a combination of machinery & parts of machinery which whether known or unknown have never before been combinedly in Rail Road Carriages or Locomotive Steam Engines. All which improvements are designated in this instrument in describing the "Locomotive or Locomotor" a name adopted to designate the whole consisting, modification and combination,

What I claim as my improvement is the particular feature of combining the Machinery as used in The Pennsylvania Locomotor as described in the following order viz., First the wheel or constructed of cast iron in a wheel of any convenient diameter and containing such number of spokes as may be deemed desirable. The rim of the wheel is furnished with

two, larger size, one as usual projecting outward from the tread or bearing surface of the wheel and serving as a guide to keep the wheel upon the rail & the other believed to be new as respects all carriage wheels projecting inward on the opposite side, ^{inner side and serving as a guide for return to the outer side of the rail.} & at the same time to the spokes with both of which it is incorporated. The hub of the wheel is of a tubular form of nearly the same thickness through as may be & that thickness being the same as nearly as may be with that of the other parts of the wheel. The equality and correspondence in thickness is believed also to be new as respects all carriage wheels and of a diameter large enough to receive boxes for the reception of the axles. The hub may be furnished with one or more flanges as may be deemed desirable viz. with one flange projecting inward from its tubular periphery on the outside of the hub & with another projecting outward and inward on the inside of the wheel. The combination of these flanges is believed by the applicant to be new.

In case of the hub being constructed without flanges two boxes will be required for each hub viz a box entering the hub on the outside & a similar box entering it from the inside of the wheel, both of which boxes are to be furnished with flanges projecting beyond the exterior periphery of the hub & serving for the reception of some bolts which pass between the spokes of the wheel and firmly connect the flanges together. This application of flanges to boxes of carriage wheels is believed by the applicant to be entirely new. In case the hub is furnished with flanges the use of the former may be enlarged at pleasure. Both flanges must be perforated for the reception of a box entering from the outside of the wheel and penetrating this interior flange which last in its projection beyond the periphery of the hub will serve for the reception of some bolts which in this modification will firmly connect the flanges of the box to the flanges of the hub. In this case the flange of the

low may be extended in a manner to subserve the purposes of a caulk which application of it, if made well, as the applicant believes be entirely meet. Changes as differences may be added to the spokes if required. This mode of constructing wheels for Rail Road Cars is such that a degree of uniformity in the thickness of every part of the hub may be successfully maintained - whereby the strain or stress usually left upon a wheel either in the unequal crystallization and cooling of the metal, or in the ordinary mode of binding & wedging of the hub, when cast in segments, may be readily obviated without impairing the strength of the wheel or rendering its construction more expensive. Second. Hubs, and their adjustments, are of a character differing from those of ordinary Rail Road Cars, and are believed to be new, as regards carriages & machinery in the following particulars. The axles are of a uniform size or nearly so throughout their entire lengths, no journals, necks, or shoulders or other irregularities being necessary in this construction. They are firmly connected to the wheel by means of brads, pins, of a suitable size passing thro' their extremities and thro' those parts of the road or boxes that are inserted within the hub, so that the hub effectively prevent the brads, pins from dropping out of their places. (The usual wedge pins may be added at the pleasure of the constructor.) Instead of journals or necks, bearing and steps or bearings in the usual manner bands, or rings, are substituted with or without washers, on either or on both sides of the band which together with the washers when applied are placed within a groove or cavity in the steps or bearings which not only serves as a receptacle for the band and washer but also as a reservoir for grease or oil for lubricating the axles. The ring or band is firmly attached to the axle by means of two or three pins or loops of suitable size passing thro' the pinholes & pinulating the axle to the depth of about one quarter of an inch & in a direction toward the centre of the ring. The exterior

as of the wheels when applied to Locomotive Engines are applied with fingers prolonged in such a manner as to subserve the purpose of combs, or a substitute for combs may be found at the place, use of the spikes insinuating a receptacle for the combs and to one or more of the spokes as hereinafter detailed. Third. Brakes or combs may be applied to the wheels in the following manner. Between the foremost and hindmost wheels on either side of each of the four wheel cars may be placed a brake of a triangular form or of the form of a wedge truncated at its point with sides gradually concave which is made to act on the peripheries of the two collateral wheels whereby being thrust upward or downward like its concave sides come into contact with the peripheries or rims of the wheels on which they are intended respectively to operate. The position of the brake or Brakes may be either above or below a line passing horizontally thro' the centres of the wheels acting in thrusting upward in the latter case and downward on the former. The brake may be made to perform its office by means of a lever, screw or pulleys at the option of the constructor. This mode of employing brakes or combs is believed to be entirely new. Fourthly. The boiler is of a cylindrical form standing on end and terminated at its upper extremity by the periphery of a direct cone, the summit of the frustum affording an area sufficient for the manhole thro' which the boiler may be entered at its top. The inside of the boiler presents also the peripheries of a direct cone the interior of which serves as a fire place. This form of construction of the boiler is new and was invented by me but was published in the Franklin Journal in 1827. The frustum in this case instead of being terminated at the top by a plane area contains a basin of a hemispherical shape insinuating its concavity toward the fire place. The diameter of the fire place at the base of this frustum is three to four inches less than that of the external part of the boiler and at the summit of the frustum the same is made less than that of its base.

Within the basin above mentioned are placed four quadrantal vessels which contain a hemispherical chamber within the basin of a diameter three to four inches less than that of the basin or of the top of the frustum on which the basin is set. Each vessel is furnished with a tube or piping rising considerably above the extreme height of water of the boiler & communicating with the steam chamber at the top & within the central head of the boiler. The whole of this arrangement of quadrantal chambers is believed to be entirely new. The boiler is prepared by circular openings leading from the fire place into the sides of the boiler. The largest side of these openings which is about ten inches in diameter serves as a fire door for the admission of fuel to the fire place and at the same time as a fire in conjunction with the other openings to convey the heated air & smoke etc from the fire place. The boiler is surrounded by a double casing of sheet iron serving as a flue to conduct the heated air & smoke from the flues just before mentioned around the exterior of the boiler. The heated air is conveyed thro' the casing of the boiler by means of two other flues passing outward from opposite sides of the boiler and then upward on the outside of the casing to the top of the boiler where they unite and pass upward in a single flue or chimney. Near the points at which the two flues last mentioned pass from the boiler casing are tubular rivets firmly by means of which the flues and chimney may be thrown into a vertical or oblique position as occasion may require either to increase the draught thereon. The fire place or to pass under a bridge or thro' a tunnel. When used in a carriage the method of construction of flues or chimney by means of the tubular rivets is believed to be entirely new. The fire grate is within the conical frustum of the boiler at its lower extremity and is constructed of wrought iron plates about one fourth of an inch thick. The grate bars are attached to a wrought iron ring of about the same thickness. The bars and the ring have nearly a uniform depth of about four inches. The bars are formed of plates of a width about

double the depth of the grate. The plates being folded longitudinally in such a manner as to form bars supporting about half an inch thick on their lowermost 4 in and a half with thick on their uppermost edges and bearing a recess of approximately from on the body of each bar. This cavity is filled with fire clay or other suitable nonconductor of heat. This method of supporting grates is believed to be new.

The grate is made to stand on a bolt or each streets beneath the grate, passing transversely across the bars, and occupying a position about one third part of the diameter of the grate, either from its point or near on the side most remote from the rail. The grate is sustained by a bolt passing under that side & capable of being withdrawn at pleasure when not it becomes necessary to discharge the fuel from the fire place. The withdrawal of the bolt being accounted by a disengagement of that part of the grate which was sustained by it & the consequent turning of the grate upon its axle which precipitates the fuel from the fire place. The ash pit is provided with an inclined flooring or apron of sheet iron the front & rear of which may be respectively elevated or depressed at pleasure not only for the purpose of regulating the draught into the fire place but to prevent the burning, overcharged with ashes, cinders, &c. The inclination serving to facilitate the discharge of any substance that may fall from the grate - either or both of the bolts by which the apron is sustained may be withdrawn whenever it becomes necessary to clear away the contents of the fire place and the apron entirely removed from the ash pit. This arrangement is believed to be new.

Fourth. the working or steam cylinder of which there are two arranged horizontally within the body of the carriage & communicating their action respectively in lines parallel to the side of the carriage frame. These centers are elevated about four inches above the centers of the carriage wheels they receive the steam from the boiler through a single steam chest which is furnished with two check valves, one for each cylinder, the movement of which are regulated in a manner to cut off or interrupt the steam in its passage into each cylinder at about one half the stroke of the piston - The application of two horizontal cylinders & their arrangement

of the steam thro' a single steam chest as believed to be new.
(Plate 3). The apparatus by which the valves are moved consists of a compound cam & four Cam rods operating in such a manner that the wheel of the carriage may be made to move in either direction at pleasure by throwing two of the Cam rods into gear & the other two out of gear. The compound cam is attached to one of the carriage axles and consists of four simple cams combined in such a manner as to contribute to the operation above mentioned. which is effected by arranging the upper, or working parts of each cam about Ninety degrees in advance of the corresponding parts of the cam that operates in conjunction with it and by a similar arrangement in relation to the other cams. The cam rods are thrown into gear and out of gear by means of a compound crank to which together with small sleeves connecting the cam rods are attached by with the compound cranks, which crank and cranks being turned to one extremity of their range bring onto action one pair of the rods & release the other pair and vice versa when the crank and crank are turned to the opposite extremity when they are turned to a point midway of their range both pairs of rods are thrown out of gear & the steam valves are entirely disengaged from them & may be moved by hand as occasion may require. This mode of adjustment of the cams and cam rods is believed to be entirely new.

Secondly. - The carriage frame consists of four chuck pieces (fig. 2) on each side of the carriage one above the other below the axles connected by timbers or cross timbers which serve not only to connect the chuck pieces, but to sustain the cylinder, boiler, bell cranks & other parts of the machinery. - The frame is suitably braced and stiffened by the pedestal on which the boiler rests by the timber comprising the bed of the cylinder & by diagonal stays of iron contributing to produce stiffness not only in the horizontal but in the vertical directions of the frame, a body of the carriage. - The entire carriage and machinery except the wheel & axle & the part immediately ^{connected} with the latter are sustained in springs by means of small iron strips attached to the lower spring pieces or cheeks and depending from the extremities of the springs. The connection of the wheel & axle with the carriage frame on a

the elevation longitudinal of the latter is effected by means of two iron bars situated about midway between the upper floor and string pieces one on each side of the carriage connected with the truck bearings or steps in which the axle turns. The check, trunnions, &c are constructed of oak in each weighing about four making square. The bolts, rods, &c by which they are connected are about three fourths of an inch in diameter. The relative disposition of the connecting bars, the axle, & the steam cylinder together with these several adjustments are believed to be new.

Eighth. - The safety valve is constructed in conformity to a principle devised and recommended by Charles Willcock Esq. of Hill, a steam engineer as my invention the application and mode of construction of the apparatus by which the principle is applied. It has for its object the prevention of a counter current of steam from acting upon the upper surface of the valve and thus contributing to force the valve downward in a manner to prevent the salutary operation of this important appendage of the steam engine. My manner of applying this principle to Locomotive and other steam engines, is as follows, viz. ... a valve chamber of a circular form & of a size sufficiently large to contain the valve and its seat. To admit the passage of steam on all sides of the valve is made of cast iron or brass & attached either to the boiler or to a steam tube leading from it.

On one side of the chamber is an aperture leading from it at a point about equal in height to that of the valve seat, which last is situated two & a half inches above the bottom of the chamber & occupies the summit of a cylindrical tube rising & that extends within the chamber. The valve chamber is furnished with a cap or bonnet not fully adjusted to its top and perforated for the reception of the valve which is of a cylindrical form having a diameter equal to that of the aperture in the valve seat. The bonnet is furnished with a plunger, box and follower by means of which the valve may be made to pass steam tight or nearly so thro' the cap of the chamber. The valve is also perforated from its top longitudinal to within about half an inch of the first setting on the valve seat for the reception of a small iron

rod or stem which serves to communicate the action of the weight to the valve. The diameter of this projection is somewhat greater than the ^{1/2} of the stem, in order to prevent the latter from impinging against the side of the valve, thereby causing the friction in the movement of the latter. The valve has also a stem thrusting downwards thro' the valve seat and entering a guide situated at the bottom of the tube on which the valve rests. As is usual in reference to ordinary safety valves, by means of this arrangement the valve stem instead of passing upwards by the sides & striking upon the upper surface of the valve is made to enter the chamber by raising the valve and afterwards to pass out at the aperture in the side of the chamber. It rests as before mentioned at or below the valve seat. ¹⁵ **Method.** In accordance with a principle claimed and successfully tested by Messrs. J. P. Mathew & Co. of Philadelphia which recognises the utility and advantage of injecting a current of steam into lignite anthracite coal as a means of promoting combustion increasing inflammation & consequently of diffusing more effectually the heat generated from anthracite and perhaps other coal. I have adopted as plan of introducing a current of steam which is discharged from the cylinder or from the safety valve immediately beneath the furnace of the boiler of Locomotive & other steam engines & above only the application of this principle to Locomotive Engines. This object I effect in the following manner. The cylinder steam tube leading from the cylinder communicates not only with the escape or waste pipe but with a pipe leading directly to the furnace. The pipe last mentioned being furnished with a cock to regulate the quantity of steam to be injected into the furnace.

Between the cock & the furnace the steam may be conveyed thro' any number of tubes that may be deemed desirable. I injected into the furnace thro' an equal or greater number of apertures. The steam tube leading from the safety valve has also similar communication with the escape pipe & the tube leading from the furnace. (Note.) The Messrs. Mathew & Co. have granted to the petitioner the privilege of specifying the principles disclosed

7372X

by him as required in the eighth and ninth article of the foregoing specification to the Locomotive and other steam engine
strength. A water tank of the capacity of about three barrels is
attached to the Locomotive beneath the cylinder and Bell crank
"struttes".
